UNITED STATES PATENT OFFICE.

EMIL FITTERS, OF CREFELD, GERMANY.

DYNAMIC AND EFFICIENCY METER.

Application filed November 1, 1922, Serial No. 598,451, and in Germany November 8, 1921.

My invention relates to counters, more especially for ascertaining and indicating and/or recording any data, for instance the performance of a steam engine within a predetermined time interval.

If a steam engine, for instance a locomotive, were operated continuously at uniform admission and uniform steam pressure, its performance might be measured by counting the strokes of the piston or pistons or the revolutions of the shaft or axle by means of a counter, a recording device or a combination of both. In practice, however, the degree of admission and the steam pressure are not uniform.

Assuming first that the steam pressure is uniform, it is necessary to ascertain the influence of various degrees of admission on the performance during one revolution of the engine, and to operate a counter in proportion to this interconnection of degree of admission and performance, so that the counter will indicate the actual performance at the predetermined degree of admission.

The means for attaining this object is old in the art, being a cam operating the counter. The cam is controlled by the means for regulating the degree of admission so that a definite position of the cam corresponds to each degree of admission. The performances of the engine at the various degrees of admission are marked on the cam so that for each revolution the performance corresponding to the given degree of admission is indicated by the counter.

In practice, however, the steam pressure is not uniform either and this may be considered by designing cams for a constant degree of admission, and variable steam pressures.

According to my invention I build up a rotary element which is constituted by a set of cams, each cam corresponding to the performance at a given steam pressure, and I provide means for adjusting said element in accordance with the existing conditions of admission and steam pressure.

In a preferred embodiment of my invention in which the counter is adapted to a steam engine, for instance a locomotive, I provide means for rotating the element from one of the controls of the engine, for instance the gear for regulating its degree of admission, and I provide means for imparting axial reciprocation to the element from another control of the engine, for instance its throttle. Conversely, I may provide means for recip-

rocating the cam from the throttle and for rotating it from the control for the degree of admission, without departing from my invention.

In the drawings affixed to this specification and forming part thereof, a counter embodying my invention is illustrated diagrammatically by way of example as adapted to a locomotive.

In the drawings

Fig. 1 is an elevation showing the arrangement of the counter and its accessories in the cab of a locomotive,

Figs. 2 and 3 are sections on the lines II-II and III-III of Fig. 1, respectively, and

Fig. 4 is a diagram which serves for explaining the theory of the instrument.

Referring now to Fig. 1, 1 is the reversing screw of a locomotive, A is the bracket in which the screw is carried, B is the handle of the screw and C is its reach rod which extends through an opening in the front wall D of the cab.

2 is a bevel gear at the end of the reversing screw, 2' is a bevel gear which meshes with the gear 2 and is secured on a shaft 3 which is carried in suitable bearings on the bracket A, 4 is a cam element on the shaft 3 which is keyed thereto so as to partake in its rotation, 5 is a double-armed lever which is fulcrumed on a suitable bracket at the wall D and linked to the Bourdon tube of a pressure gauge 6, 6' is the steam pipe connecting the gauge with a valve chest or the valve chests, not shown, of the locomotive, 7 is a rocking lever, 8 is a roller at its front end which is adapted to cooperate with the cam element 4, 9 is a suspension link by which the lever 7 is carried on the bracket A, 9' is a spring which is attached to the suspension link 9 at one end and to the upper bearing of the shaft 3 at the other so as to hold the roller 8 engaged with the face of the cam element 4, 11 is an eccentric to which rotation is imparted from any moving part, for instance the speedometer shaft 12, so that rocking motion about the centre of the roller 8 is imparted to the fork-shaped end of the lever 7, 13 is a parallel guide secured to the bracket A, 14 is a slide block in the guide, 15, 15 are curved jaws on the block which engage the lever 7 on either side, 16 is a pawl linked to the slide 14, and 17 is a ratchet wheel on a counter 18 which is secured to the bracket A so that its dial is visible to the driver.

Referring now to the diagram, Fig. 4, a is the constant distance of the longitudinal axis of the slide 14 from the eccentric shaft 12, h is the, also constant, stroke of the eccentric 5 12, y is the variable stroke of the pawl 16 which corresponds to a given admission and a given steam pressure in the valve chest and may be calculated or plotted from a steam 10 diagram, and x is the variable distance of the axis of the roller 8 from the axis of the slide 14. The distance x is calculated as follows:

15

$$\frac{x}{y} = \frac{a}{h-y}$$

$$x = \frac{ay}{h-y}$$

Instead of plotting the performance of a locomotive against the steam pressure and 20 configurating the curve of the cam element 4 accordingly, I may also generate the curve by automatic means. In this case, the rocking lever 7 and the parts cooperating therewith are duplicated in a machine tool and the 25 roller 8 at the end of the lever 7 is replaced by a milling cutter. The eccentric 11 is stationary and the slide 14 is adjusted in accordance with the output indicated on the counter 18. In this manner the curve of the cam element 30 4 will be obtained automatically.

In some cases it may be desirable to register 35 separately the performance of the locomotive when it runs light or with only a few cars on, that is, to determine the proper resistance of the locomotive or, in addition that of cars which are generally present, for instance the mail and luggage vans. In such cases, a second counter 21 may be provided which is carried at the end of an angular lever 19. The 40 lever 19 is fulcrumed to the bracket A at 20 and is provided with a gear wheel or the like 22 by which it is connected with, and driven by, the counter 18 when the lever 19 is rocked on its pivot correspondingly. An arm 19' is

formed on the suspension link 9 in such a position that it causes the two counters 18 and 45 21 to become connected under the above-mentioned conditions of light load and the output will now be registered separately by the counter 21. Beyond the limit of the said 50 small performance, the counter 21 is automatically released by the arm 19'.

Recording means may be provided in connection with the gauge 6 and with the pawl 16 so that the performance of the locomotive 55 is directly registered instead of being only indicated by the counters.

It will be understood that by setting the reversing screw 1 for a given admission and by opening the throttle valve to a certain extent, a given position will be imparted to the cam element 4 with regard to the roller 8 and the distance of the roller 8 from the eccentric shaft 12, $a+x$ in the diagram Fig. 4, will be adjusted accordingly. A given value of x 60 65 corresponds to each of these positions.

I claim:

1. A counter for ascertaining the performance of a steam engine comprising indicating means, a rotary cam element for operating said means, means connected with the means for regulating the degree of admission of said engine and adapted to impart rotation to said cam element, and a pressure gauge adapted to impart axial reciprocation to said 70 75 element.

2. A counter for ascertaining the performance of a steam engine comprising indicating means, a rotary cam element for operating said means, a pressure gauge adapted to impart axial reciprocation to said cam element, and means connected with the means for regulating the degree of admission of said engine and adapted to impart rotation to said 80 85 cam element.

In testimony whereof I affix my signature.

EMIL PETERS.
